HINGE

Walter E. Woodin, Jamestown, N. Y., assignor to
Jamestown Metal Equipment Company, Inc.,
Jamestown, N. Y., a corporation of New York

Application June 10, 1932, Serial No. 616,476

12 Claims. (Cl. 16—171)

This invention relates to an improvement in hinges and more particularly to the single knuckle type.

The preferred embodiment of the invention discloses a hinge having an arrangement for preventing the removal of the leaf elements from each other except at a predetermined point.

Prior to this invention hinges of the single knuckle type have been formed from leaves which, while often exact duplicates, produced a dissymmetric unit when assembled. The result of this dissymmetry amounts not merely to an artistic objection but indicates that, by reason of the reversal of the connecting leaves, the attaching portions are not alike. Consequently, it sometimes occurs that mortises are incorrectly cut into the door and jamb simply because the workman has had to cut dissimilar mortises and located the door mortise on the jamb. The present invention discloses a pair of hinge leaves, the shank portions of which are of the same size and in the same plane. This is a distinct advantage since it permits the use of symmetric mortises in both door and jamb, the mortise being also symmetric with respect to its own center line. Since the mortise in both door and jamb are identical in height, depth and location, no error in mounting a hinge of the type hereinafter disclosed can occur. A further disadvantage of currently manufactured hinges of this type will be noted from the fact that due either to inaccurate manufacturing or improper mounting or assembly, an unsightly gap occurs between the engaging surfaces of the upper and lower knuckles. The present invention, through the provision of a collar attached to or abutting one of the knuckles and having a recess into which the other of the knuckles projects, overcomes this objection and at the same time provides a lubricant reservoir for the relatively movable elements. It is by means of this recess that any lubricant applied to the hinge is concealed from view and prevented from appearing on the outer surfaces of the knuckles. A still further objection to the current hinges of this type lies in the fact that the elements thereof may be readily separated. It sometimes occurs that a door supported by a hinge of this type receives an upwardly directed force which tends to or actually does disengage the hinge elements. To prevent this, the present invention discloses means by which to lock the elements in operative relationship through the use of the same collar which constitutes the lubricant retaining element.

The objects of the invention are, therefore,

the provision of hinge elements which are locked in pivotal engagement with each other throughout the greater part of their working range; means for concealing the abutment of relatively movable elements; provision of symmetric leaves for permitting symmetric mortising; and a lubricant retainer for the relative movable elements.

Other and further objects of the invention will be more clearly understood from a consideration of the following specification which is taken in conjunction with the accompanying drawing, and in which

Fig. 1 shows a perspective view of a hinge partly in section to show the elements in their normal relationship to each other;

Fig. 2 is a plan view of one of the leaves;

Fig. 3 is a plan view of the other leaf, showing the anti-friction collar in position;

Fig. 4 shows a fragmentary elevation of the hinge, parts being broken away to show how the leaves are locked to prevent separation thereof; and

Fig. 5 is a perspective view of the anti-friction collar.

Referring to the drawing and particularly to Figure 1, the invention, generally indicated by the reference numeral 10, is shown comprising a pair of elements 11 and 12. The element 11 comprises a door mounting portion 13, a shank portion 14 and a knuckle 16. Openings 17, in the portion 13, are adapted to receive screws for attaching the element to a door. The element 12 comprises a frame mounting portion 18, shank portion 19 and a knuckle 21, and is adapted to be attached to a frame by means of screws which project through openings 22 in the portion 18. The shank portions 14 and 19 project from one edge of the portions 13 and 18. The knuckle 16 is integrally formed on the upper portion of the shank 14 and terminates at its lower end in a flat bearing face 23. Similarly the knuckle 21 is formed on the lower portion of the shank 19 and terminates at its upper end in a face 24. It is pointed out that, although the elements 11 and 12 of the hinge are shown to be substantially identical, it is contemplated to make use of a hinge of this type for purposes wherein one of the elements may be entirely disproportionate to the other. For example, a hinge of this type may be utilized to support an automobile door or any other door in which the mounting thereof is not in accord with the standard entrance door mounting in which the elements of a hinge are substantially duplicate.

Openings 26 and 27, drilled axially a limited

depth in the knuckles 16 and 21 from the surfaces 23 and 24, are each adapted to receive an equal portion of a pivot pin 28. The opening 27 is preferably a drive fit for the pin 28 to prevent removal thereof from the knuckle 21. This knuckle may also be shrunk on the pin by applying heat, then allowing the knuckle to cool while the pin is in place. The knuckle 16 engages the upper portion of the pin 28 in a manner which will permit 10 free rotation thereabout.

Permanently mounted on the mid-portion of the pin 28 is an anti-friction thrust collar 29. The lower face of the collar, when in place, abuts the face 24 of the knuckle 21. A recess 31 formed in the upper face of the collar 29 receives the face 23 of the knuckle 16. This recess acts as a reservoir for retaining surplus lubricant and also as a means for concealing any gap which may occur between faces 23 and 24 which may result 20 from an inaccurate mounting of the elements. The peripheral edge of the collar is preferably semi-circular in section and projects beyond the lateral confines of both knuckles to form a shoulder 32. A slot 33, of slightly greater width than the thickness of shank portions 14 or 19, is cut in the peripheral edge of the collar 29, the purpose of which will hereafter be described.

Adjacent the shoulder 32 and located centrally on the shank 14 is a notch 34 which may conform to the contour of the shoulder 32. The lower wall of the notch 34 is adapted to engage the lower surface of the shoulder 32 to prevent separation of the elements 11 and 12.

The slot 33, when the elements are located in a predetermined relative position, registers with the shank portion 14. Since the slot is of a width and depth to receive said portion, the elements may be disengaged. It should be understood that there is but one definite relative angular position of the elements where separation or assembly 40 can take place. In other words, when the hinge is assembled the elements are locked in pivotal engagement with each other in every angular position except one. The notch 33 may be located in any convenient position relative to the mounting portion and shank. In the present showing, the shanks and mounting portions must be parallel and extend in the same direction before assembly or separation of the elements can take place.

It will be noted that the recess 31 provides a reservoir for lubricant and prevents any surplus oil or grease from smearing the outside of the elements. The walls of the recess are adapted to 55 conceal any small gap between engaging surfaces which may occur as a result of an inaccurate location of one of the elements on a door or frame.

Although applicant has shown and described but one modification of his invention, it is obvious to those skilled in the art that other modifications or adaptations may be made without departing from the spirit and scope of the invention as defined in the hereunto annexed claims.

Having thus set forth my invention what I claim as new and for which I desire protection by Letters Patent is:

1. A hinge comprising a pair of reversely disposed elements, duplicate knuckles formed integral with said elements, a pivot pin connecting said knuckles, means interposed between said knuckles for securing said knuckles in operative relationship with each other, said means including further means for allowing said knuckles to

be separated when said elements are rotated to a predetermined position.

2. A hinge comprising a pair of elements having shank portions, a knuckle on each of said shank portions, a pivot pin connecting said knuckles, means interposed between said knuckles, said means providing a shoulder, further means in one of said shank portions for engaging said shoulder, said means and said shank portion means cooperating to secure said knuckles in operative relationship.

3. A hinge comprising a pair of elements having shank portions, a knuckle on each of said shank portions, a pivot pin connecting said knuckles, a collar interposed between said knuckles having a shoulder of a diameter greater than that of said knuckles, one of said shank portions having a notch for receiving said shoulder, the walls of said notch and said shoulder cooperating to retain said knuckles in operative relationship.

4. A hinge comprising a pair of elements having shank portions, a knuckle on each of said shank portions, a pivot pin connecting said knuckles, a collar interposed between said knuckles, an annular shoulder on said collar of a diameter greater than that of said knuckles, means in one of said shank portions for receiving said shoulder, and means in said shoulder, the means of said shank portion cooperating with said shoulder to secure said knuckles in operative relationship, and said shoulder means cooperating with said one shank portion to allow said knuckles to be separated.

5. A hinge comprising a pair of substantially identical elements having knuckles integrally formed thereon, a pin pivotally connecting said knuckles, an anti-friction collar interposed between said knuckles, the peripheral edge of said collar projecting beyond the confines of said knuckles to form a shoulder, walls defining a notch in one of said shank portions registering with said shoulder, said notch and said shoulder cooperating to retain said knuckles in operative relationship.

6. A hinge comprising a pair of elements having knuckles formed thereon, a pivot pin connecting said knuckles, a collar fixed relative to one of said knuckles and interposed between and projecting beyond the lateral confines of said knuckles to form an annular shoulder, one of said elements having a notch for receiving said shoulder, said shoulder having a slot adapted to receive and vertically release one of said elements whereby said knuckles may be separated when rotated to a predetermined position.

7. A hinge comprising a pair of elements having knuckles formed thereon, walls defining axial openings in said knuckles, a pin secured to one of said knuckles and projecting into the opening in the other of said knuckles, an anti-friction collar secured to said pin and interposed between said knuckles, said collar having an annular shoulder projecting beyond the lateral confines of said knuckle, one of said elements having a notch for receiving said shoulder whereby to prevent pivotal disengagement of said elements from each other.

8. A hinge comprising a pair of substantially identical elements, knuckles integral with said elements, a pin pivotally connecting said knuckles, means interposed between said knuckles and projecting beyond the confines thereof to form an annular shoulder, projections defining a notch in one of said elements for receiving said shoulder, a slot in said shoulder, said projections and

- said slot being in register when said elements are in a certain relative position to allow separation or assembly of said elements, said shoulder and one of said projections cooperating in all 5 other relative positions to secure said elements in operative relationship.
9. A hinge comprising a pair of elements having symmetrical shank portions, a knuckle on each of said shank portions, a pivot pin fixed with 10 respect to one of said knuckles and removably and rotatably interfitted with the other of said knuckles, means mounted on and secured against rotation relative to one of said knuckles, said means being interfitted with one of said shank 15 portions and serving therewith to retain said hinge elements in operative pivotal relationship.
10. A hinge comprising a pair of elements having symmetrical shank portions, a knuckle on each of said shank portions, a pivot pin connecting 20 said knuckles, a collar secured against rotation relative to one of said knuckles and interposed between and projecting beyond the lateral limits of both of said knuckles to form a shoulder, one of said shank portions having a notch for 25 receiving said shoulder, said shoulder having a slot for receiving and vertically releasing one of
- said shank portions whereby to permit disengagement of said elements.
11. A hinge comprising a pair of elements, duplicate knuckles formed integral with said elements, a pivot pin connecting said knuckles, 80 means on said pin interposed between said knuckles, said means forming with said knuckles a symmetrical pivot portion of said hinge, said means including further means engageable with one of said elements for retaining said elements 85 in operative pivotal relationship.
12. A hinge comprising a pair of elements, shank portions on said elements having symmetrical proportion, a knuckle on each of said shank portions, a pin mounted on one of said 90 knuckles, means on said pin in abutment with and fixed relative to the pin mounting knuckle, said means interfitting with the other of said knuckles and having a shoulder projecting beyond the lateral limits of both of said knuckles, 95 one of said shank portions being notched to receive and interfit with said shoulder whereby to retain said elements in operative pivotal relationship.
